UNITED STATES PATENT OFFICE.

ANDREW J. O'BRIEN, OF JERSEY CITY, NEW JERSEY, ASSIGNOR TO THE NEW JERSEY CAR SPRING & RUBBER COMPANY, OF JERSEY CITY, NEW JERSEY, A CORPORATION OF NEW JERSEY.

DESIGN FOR A MAT.

No. 37,684.

Specification for Design.

Patented Nov. 21, 1905.

Application filed June 27, 1905. Serial No. 267,320. Term of patent 14 years.

To all whom it may concern:

Be it known that I, ANDREW J. O'BRIEN, a citizen of the United States, residing in Jersey City, county of Hudson, and State of New Jersey, have invented a new, original, and ornamental Design for a Mat, of which the following is a specification.

The accompanying drawing is a plan view of a mat, showing my new design.

I claim—

The ornamental design for a mat as shown.

ANDREW J. O'BRIEN.
